UNITED STATES PATENT OFFICE

FRANK W. ANDREWS, OF DAYTON, OHIO, ASSIGNOR, BY MESNE ASSIGNMENTS, TO
FRIGIDAIRE CORPORATION, A CORPORATION OF DELAWARE

REFRIGERATING APPARATUS

Application filed April 28, 1927. Serial No. 187,351.

This invention relates to cooling devices, termed units or coils for refrigerating apparatus. It is particularly, tho not exclusively, adapted to refrigerating cabinets of the 5 household type.

It is among the objects of the invention to provide an improved cooling unit which will freeze ice quickly and at the same time effectively cool circulating air for refrigerating a cabinet and to provide a cooling unit which is simple and inexpensive to manufacture and install.

Further objects and advantages of the present invention will be apparent from the 15 following description, reference being had to the accompanying drawings, wherein a preferred form of embodiment of the present invention is clearly shown.

In the drawings:

20 Fig. 1 is a front elevation of a refrigerating cabinet provided with a cooling coil according to the present invention;

Fig. 2 is an enlarged section of a portion 25 of a cabinet showing the cooling coil in elevation; and

Fig. 3 is a side elevation of the cooling coil removed from the cabinet.

In Fig. 1, 10 designates a refrigerating cabinet which may have a cooling compartment 11, one or more storage compartments 12, doors 13 and a machine compartment 14. The cooling compartment may be conveniently provided by an L-shaped partition 15 placed in the corner of the cabinet and provided with air circulating openings 16 and 17.

According to the present invention I make the cooling unit or coil of a single continuous piece of pipe or tubing 20 which is 40 wound into a series of coils 21. Each coil consists of a plurality of loops which may be made by winding the pipe into the general shape of a comb, or preferably as shown in the drawings, by winding the pipe into a 45 serpentine form. A series of these serpentine coils 21 is formed and, as shown in Fig. 3, they are placed in parallel planes 50 preferably contiguous to each other. The coils in each plane are wound with their loops reversed with respect to the coils in

the adjacent planes as shown in Fig. 2, so that the corresponding loops of all of the coils co-operate to form enclosures for ice-making receptacles 30.

Preferably sleeves 31 are placed within the enclosures thus formed and are secured in intimate thermal contact with the coils, for example, by soldering. These sleeves are of metal of good thermal conductivity such as copper and provide shields to prevent moisture dripping from the coils into the ice-making receptacles as well as means for conducting heat from the receptacles to the coils. The loops of the coils extend laterally beyond the sleeves 31 and form cooling 55 means for currents of air circulating over the cooling unit. In the embodiment shown, the unit is supported in the cabinet by straps 32 secured to the top of the cabinet 60 and attached to the loops by clamps 33.

The unit is placed in the cabinet with its top slightly below opening 16 so that air circulating thru the cabinet and entering the cooling compartment thru this opening passes over and around the cooling unit before it leaves the compartment thru the opening 17 at the bottom. Thus the extending portions of the loops are exposed to the circulating currents and substantially surrounded by them, providing a very effective 70 means for cooling the air. A baffle 35 may be provided above the opening 17 to prevent moisture from dripping thru the opening. This moisture may be removed from the cooling compartment by a drain 36.

The cooling unit may be supplied with any refrigerating medium, such as cold brine, which may be circulated by any suitable apparatus, but I prefer to evaporate liquid refrigerant within the coils. Such liquid refrigerant may be supplied thru a conduit 40 to an expansion valve 42 which regulates the flow of liquid to the coils. The refrigerant evaporated in the coils is removed thru the suction pipe 43. Any suitable apparatus may be used for this purpose such as the usual motor driven compressor and condenser (not shown) which for convenience may be placed in the machine compartment 13 as is well known in the art.

It will be seen that I have provided a cooling unit which has means for effectively cooling circulating air and which at the same time provides a plurality of complete enclosures for ice-making receptacles and therefore has a large ice-making capacity. The arrangement described is particularly effective in constructing a cooling unit for a large number of ice-making pans, since 10 refrigerant will circulate between and around each of the pans irrespective of their number.

While the form of embodiment of the present invention as herein disclosed, constitutes a preferred form, it is to be understood that other forms might be adopted, all coming within the scope of the claims which follow.

What is claimed is as follows:

20 1. A cooling unit for refrigerating apparatus comprising a single continuous conduit formed into a plurality of planar coils, each coil consisting of a plurality of loops, the coils being disposed in parallel planes and 25 the loops of each coils being reversed with respect to the loops of the adjacent coils to form a plurality of enclosures for ice-making receptacles.

30 2. A cooling unit for refrigerating apparatus comprising a single continuous conduit formed into a plurality of planar coils, each coil consisting of a plurality of loops, the coils being disposed in parallel planes and contiguous to each other, and the loops of 35 each coil being reversed with respect to the loops of the adjacent coils to form a plurality of enclosures for ice-making receptacles.

40 3. A cooling unit for refrigerating apparatus comprising a single continuous conduit formed into a series of serpentine coils, the coils being disposed in parallel planes and the loops of each coil being reversed with 45 respect to the loops of the adjacent coils to form a plurality of enclosures for ice-making receptacles.

50 4. A cooling unit for refrigerating apparatus comprising a single continuous conduit formed into a series of planar coils, each coil consisting of a plurality of loops, the coils being disposed in parallel planes and the loops of each coil being reversed with respect to the loops of the adjacent coil to 55 form a plurality of enclosures for ice-making receptacles, compartments for ice-making receptacles within said enclosures, the loops of the coils extending laterally beyond the compartments to cool circulating air.

60 5. A cooling unit for refrigerating apparatus comprising a single continuous conduit formed into a series of planar coils, each coil consisting of a plurality of loops, the coils being disposed in parallel planes and the loops of each coil being reversed with 65 respect to the loops of the adjacent coils

for forming a plurality of enclosures for ice-making receptacles; compartments for ice-making receptacles within said enclosures, the loops of the coils extending laterally beyond the compartments; and means 70 for supporting the cooling unit in a cabinet secured to the extending portions of said loops.

In testimony whereof I hereto affix my signature.

FRANK W. ANDREWS.
